WIRE COIL CARRIER

Robert A. McMasters, Birmingham, Ala., assignor to
Southeastern Metals Company

Filed June 9, 1960, Ser. No. 60,907

Term of patent 14 years

(Cl. D58—5)

FIG. 1.

FIG. 2.

FIG. 3.

FIG. 4.

FIG. 1 is a perspective view of a wire coil carrier, embodying my new design;

FIG. 2 is a top plan view thereof;

FIG. 3 is a side elevation of the front of FIG. 2; and

FIG. 4 is a further side elevation taken at 45° to FIG. 3.

I claim:

The ornamental design for a wire coil carrier, as shown.
